(57) **CLAIM**

The ornamental design for a cassette assembly for a blind system, as shown and described.

DESCRIPTION

FIG. 1 is a top view of the cassette assembly for a blind system of the present invention;

FIG. 2 is a bottom view thereof;

FIG. 3 is a front view thereof;

FIG. 4 is a rear view thereof;

FIG. 5 is a top left perspective view thereof;

FIG. 6 is a top right perspective view thereof;

FIG. 7 is a bottom left perspective view thereof;

FIG. 8 is a bottom right perspective view thereof;

FIG. 9 is a left side view thereof; and,

FIG. 10 is a right side view thereof.

The cassette assembly for a blind is shown with a symbolic break in its length shown by dot-dashed lines. The appearance of any portion of the article between the dot-dashed lines forms no part of the claimed design. The dashed lines depict portions of the article that form no part of the claimed design.
